Chicago, Ill. 60657

Filed Apr. 22, 1970, Ser. No. 22,560

Term of patent 14 years

Int. Cl. D21—01

U.S. Cl. D34—5

FIG. 1

FIG. 2

FIG. 3

FIG. 1 is a top plan view of my spinning indicator device;

FIG. 2 is a side elevational view of the same, taken with the spinner disposed normal to the line of view; and

FIG. 3 is a side elevational view of the same, taken with the spinner disposed parallel to the line of view.

The bottom is plain, circular and flat. Side elevational views taken from other points of vantage are essentially identical to that shown in FIG. 2.

I claim:

The ornamental design for a spinning indicator device, as shown and described.
